UNITED STATES PATENT OFFICE.

ROBERT P. BROWN, OF PHILADELPHIA, PENNSYLVANIA, ASSIGNOR TO BROWN & BAILEY COMPANY, OF PHILADELPHIA, PENNSYLVANIA, A PENNSYLVANIA CORPORATION.

COLLAPSIBLE BOX.

No. 860,724.

Specification of Letters Patent.

Patented July 23, 1907.

Application filed September 7, 1906. Serial No. 333,594.

To all whom it may concern:

Be it known that I, ROBERT P. BROWN, a citizen of the United States, residing in the city of Philadelphia, county of Philadelphia, and State of Pennsylvania, 5 have invented certain Improvements in Collapsible Boxes, of which the following is a specification.

This invention is a collapsible box adapted particularly for holding clothing and so constructed that it can more readily be brought to the form desired and more 10 securely held in the open position, avoiding the usual instability and being operated with greater facility than usual constructions.

In the accompanying drawings, Figure 1 is a plan view of a blank of substantially rectangular form, excepting the dovetail portion cut out of the end flap 7 to form the ears 13, cut and scored according to my invention; Fig. 2 is a plan view of the collapsed box made therefrom; Fig. 3 is a perspective view of the box in the open or operative position, and Fig. 4 is a vertical sectional view taken on the line 4—4 of Fig. 3 showing an interior elevation of the end of the box.

The construction, designed for manufacture from paper board, comprises a blank with parallel longitudinal scores 1 to form joints between the bottom 2 and the 25 sides 3, the transverse scores 4 to form joints between the bottom and the ends 5, the scores 6 parallel to the scores 4 to form the infolding flaps 7, the through cuts 8 in line with the scores 1 to detach the side extensions or flaps 9 from the ends, the diagonal scores 10 to permit 30 the side extensions or flaps 9 to be folded along the score lines and permanently secured by staples or stitches 11 to the ends 5, the slots 12 in the side extensions between the diagonal scores and the stitches, and the ears 13 on the flaps 7 for engagement in the slots 12 to lock the 35 folded flaps when infolded so that their edges 14 brace the sides 3, the flaps being detachably engaged so that distortion is not required in operating them and the edges preferably extending at least half the depth of the box to form broad abutments for the sides.

It will be observed that the side extensions forming 40 the flaps 9 project beyond the scores 6 to the outer line of the infolding flaps 7 whereby there are provided when the flaps 9 are infolded as shown in Fig. 2, a suitable construction for the engagement of such flaps to the ends by the stitches 11 placed between the slots 12 45 so as not to interfere with the engagement of the ears with such slots.

This construction will be seen to involve practically no waste material and to provide a substantially flat structure with sides infolded when collapsed, the box 50 being readily opened or closed without distortion of the parts and firmly held in the operative position without the tendency to knock down found in boxes having sides that fold outwardly or having inwardly infolding sides without proper means for bracing them. 55

Having described my invention, I claim:—

1. A collapsible box formed of a blank scored to provide sides and ends and cut to form extensions of said sides, such side extensions being folded along diagonal scores, means securing said extensions to the box ends, 60 such extensions having slots therein between the diagonal scores and the point of attachment to the box ends, said box ends being provided with infolding end flaps provided with ears to engage in the slots of the side extensions.

2. A collapsible box formed of a blank scored to provide 65 sides and ends and cut to form extensions to said sides, such side extensions being folded along diagonal scores and having slots therein, and means securing said extensions to the box ends, said box ends being provided with infolding end flaps having parts to engage in the slots of 70 the side extensions and secure said end flaps to said extensions.

In testimony whereof I have hereunto set my name this 5th day of September, (1906,) in the presence of the subscribing witnesses.

ROBERT P. BROWN.

Witnesses:
